UNITED STATES PATENT OFFICE

2,259,002

CUTTERHEAD CONSTRUCTION FOR DRY SHAVERS

Raymond Knapp, Long Island City, N. Y., assignor to Knapp-Monarch Company, St. Louis, Mo., a corporation of Missouri

Application August 1, 1938, Serial No. 222,455

8 Claims. (Cl. 30—43)

An object of my invention is to provide a cutter head construction for dry shavers which is simple and inexpensive to manufacture and which includes novel features of construction whereby to improve the hair-cutting action of the shaver.

Another object is to provide a cutter head construction including an outer cutter plate formed of sheet metal and having openings therein to receive the hair, the sheet metal being depressed adjacent the edges of the openings to form grooves which guide the hair into the openings, the general direction of the grooves being substantially parallel to the line of advance of the outer cutter plate across the skin of the user.

Still another object is to provide an inner cutter which so coacts with the teeth of the outer cutter and with the sheet metal at the ends of the grooves that any hair projecting through the openings of the outer cutter plate adjacent the groove ends is effectively sheared off between the inner cutter teeth and the metal of the outer cutter plate at the ends of the grooves.

A further object is to provide means to urge the inner cutter into shearing coaction with the outer cutter, which means includes rollers, pins and spring means to urge the pins and thereby the rollers toward the inner cutter.

Still a further object is to provide the hair-guiding grooves in connection with various types of cutters, the grooves being arranged between spaced series of openings in the outer cutter plate or at the ends of transverse slots where the grooves serve to guide the hair into the slots during the return stroke of the cutter across the skin of the user.

With these and other objects in view, the invention resides in certain improvements and in a combination of parts of the device, all as will hereinafter more fully be described and the novel features will be pointed out in the claims appended to the application.

In the accompanying drawings:

Figure 1 is a sectional view through a cutter head construction for dry shavers embodying my invention, a portion of the shaver head reception end of the dry shaver motor being illustrated and a portion of the actuating arm for the inner cutter being shown in this figure;

Figure 2 is a similar sectional view showing only the skin-engaging end of the cutter, with the parts enlarged so as more clearly to illustrate the invention;

Figure 3 is a fragmentary perspective view of the outer and inner cutters, the two being shown in coaction with each other;

Fig. 4 is a sectional view on the line 4—4 of Figure 3, illustrating in end elevation, the hair-guiding grooves formed in the outer cutter plate;

Figure 5 is a side elevation of a complete cutter head construction including the inner and outer cutters, portions thereof being broken away and other portions shown in section to illustrate the coaction of different parts of the device with each other;

10 Figure 6 is an elevational view, as on the line 6—6 of Figure 5, showing a modified construction;

Figure 7 is a fragmentary side elevation of the modification shown in Figure 6;

15 Figure 8 is a sectional view on the line 8—8 of Figure 6;

Figure 9 is a sectional view, as on the line 9—9 of Figure 5, showing another modification;

Figure 10 is a fragmentary side elevation 20 thereof, and

Figure 11 is a sectional view on the line 11—11 of Figure 9.

On the accompanying drawings, I have used the reference character A to indicate an outer

25 cutter plate and B an inner cutter member. The plate A has a semi-cylindrical skin-engaging portion 10 and side plate portions 12. Between the side-plate portions 12 filter blocks 13 are pro-

30 vided and reinforcing blocks 21 are located outside the side plates 12. The outer cutter plate A, the blocks 13 and the blocks 21 are assembled by riveting them together. The rivets are indicated at 14.

The cutter plate A is provided with openings 35 such as slots 15 whereby the metal between the slots serves as outer cutter teeth. The inner cutter B has cutter teeth 16 for shearing coaction with the teeth of the outer cutter upon reciprocation of the inner cutter relative to the outer

40 cutter. Such reciprocation is effected by an oscillating arm 17 pivoted at 18 and operated by an electric motor (not shown) in a casing 19 in the usual manner.

The outer end of the oscillating arm 17 operatively 45 engages the inner cutter B by being located in a slot 20 thereof. The reinforcing blocks 21 fit snugly in an opening 22 formed in a head member 23 of the casing 19. A retainer 24, formed of leaf spring material engages a groove 25 of one of the plates 21 to firmly retain the outer cutter within the head member 23.

In connection with the operation of dry shavers, I find that the shaver has to be passed across the skin several times in order to cut all the beard. 50 I have also found that the number of such pas-

sages can be materially reduced by providing guide grooves 26 having their ends terminating at the openings 15 for guiding the hairs into the openings so that they can be sheared off.

Where the outer cutter plate is of sufficient thickness, I can cut the grooves therein. Ordinarily, however, it is desirable to have the plate quite thin or formed of thin sheet metal in which case I form the grooves 26 by depressing them into the sheet metal so that the depressed portion of the sheet metal forms an internal bead 27. This bead, in addition to serving the purpose of permitting the groove 26 to be formed in the sheet metal without materially reducing its thickness, serves to reinforce the sheet metal against bending and distortion.

The grooves 26 are arranged in the general direction of advance of the outer cutter plate across the skin of the user, or in other words transversely of the longitudinal axis of the cutter head. The grooves 26 appear as in Fig. 4, when viewed on the line 4-4 of Fig. 3, and it will be noted that this produces an offset in the sheet metal adjacent the upper ends of the slots 15. The ends of these offsets are indicated at 28. The upper ends of the cutter teeth 16 as indicated at 29 engage the shoulders formed at 28 and thereby shearingly coact with them so that any hair getting into the slots 15 and being positioned at the upper ends thereof at the time a tooth 16 passes the slot will be effectively sheared off between the portions 28 and 29.

To retain the portions 28 and 29 in shearing contact with each other and also to retain the sides of the teeth 16 in shearing contact with the sheet metal of the outer cutter plate A between the openings 15 therein I provide an improved biasing means comprising springs 30, pins 31 and rollers 32. The springs 30 are located in bores 33 formed in the filler blocks 13. They are retained therein by plugs 34 and the upper or outer ends of the springs engage the pins 31. The rollers 32 are located in the outer ends of the springs and journaled on the pins 31. The ends of the pins are located in notches 35 of the filler blocks 13 and are retained therein against being expelled therefrom by the springs 30 in any suitable manner when the inner cutter is removed from the outer cutter. By way of illustration, I show deformations at 36 in the edges of the notches 35 to accomplish this result.

There are certain types of cutter heads as shown in Figs. 6 and 9 which have transverse slots 15a extending across the outer cutter plate A' or A'' and terminating in the side plates 12a thereof. Hair guiding grooves 26a may be provided for this type of cutter arranged at the opposite ends or bases of the slots 15a. The grooves are preferably in alignment with the direction of advance of the cutter head on the return stroke thereof so that they guide the hair into the slots. Various parts in these two figures, other than those just enumerated, correspond to the preceding figures and are therefore given the same reference numeral with the addition of the letter a.

In Figure 6 the inner cutter is illustrated at B' and in Figure 9 at B''. The inner cutter B' is formed of sheet metal so shaped as to accommodate the beads 27a and is formed with an offset to provide the shoulders 28a. The inner cutter B'', in Figure 9, may be machined from a solid piece of metal and notched to form its shoulders at 28a. In Figures 8 and 11, the relationship of the inner cutter teeth 16a to the sheet metal be-

tween the openings 15a for shearing coaction therewith is illustrated.

The grooves 26 and 26a I find very effective for the purpose of guiding the hairs into the slots 15 and 15a and for aiding in the process of causing the hairs to stand erect before they enter the slots. Obviously the shearing of the hairs is thereby facilitated. The pressure of the edges of the grooves against the skin results in the portion of the skin in the grooves bulging toward the cutter head and thereby aiding in the erection of the hairs.

Some changes may be made in the construction and arrangement of the parts of my device without departing from the real spirit and purpose of my invention. I therefore intend to cover any modified forms of structure or use of mechanical equivalents which may be reasonably included within the scope of my appended claims.

What I claim as my invention and desire to protect by Letters Patent of the United States Patent Office is:

1. In a cutter head construction for dry shavers, an outer cutter plate formed of sheet metal, said plate having therein a plurality of spaced openings whereby the portions of the sheet metal between said openings form outer cutter teeth, an inner reciprocable cutter having teeth for shearing coaction with said outer teeth, a groove depressed in said outer cutter plate for each opening therein and terminating at an end of the opening, said inner cutter terminating at said ends of said openings and the metal of said outer cutter in which said grooves are formed, engaging the terminal end of said inner cutter, said grooves being arranged in a direction substantially lateral to the direction of reciprocation of said inner cutter plate relative to the skin of the user.

2. In a cutter head construction for dry shavers, an outer cutter having therein a plurality of spaced elongated openings whereby the portions of the outer cutter between said openings form cutter teeth, an inner cutter having teeth for shearing coaction with the cutter teeth of said outer cutter, a depressed groove in said outer cutter for each opening therein and terminating at an end of the opening and said inner cutter having tooth ends engaging the material of said outer cutter that was displaced in forming the grooves, said grooves being arranged substantially parallel to said elongated openings of the outer cutter plate.

3. In a cutter head construction for dry shavers, an outer cutter member having a series of openings therein arranged in a plurality of spaced groups, an inner cutter having teeth to shearingly coact with the portions of said outer cutter member between said openings and grooves in said outer cutter member between said groups of openings and aligned with the openings, the opposite ends of said grooves terminating at the ends of said openings.

4. In a cutter head construction for dry shavers, an outer cutter plate formed of sheet metal and having a series of openings therein arranged in a pair of spaced rows, an inner cutter having teeth to shearingly coact with the portions of said outer cutter member between the openings therein and grooves depressed in the metal of said outer cutter plate and arranged to extend transversely across said outer cutter plate from one row of openings therein to the other with the opposite ends of said grooves terminating at the ends of said openings.

5. In a cutter head construction for dry shavers, an outer cutter plate formed of sheet metal, said outer cutter plate having a series of openings therein arranged in a plurality of spaced groups, the portion of the sheet metal between said openings forming outer cutter teeth, a reciprocable inner cutter having teeth to shearingly coat therewith and grooves depressed in the metal of said outer cutter plate and arranged to extend between said groups of openings, the opposite ends of said grooves terminating at the ends of said openings and being arranged in a direction substantially normal to the line of reciprocation of the inner cutter relative to the outer cutter plate.

6. In a structure of the character disclosed, an outer cutter plate formed of sheet metal, said cutter plate being bent to form an arcuate outer surface and a pair of sides, elongated openings extending transversely of said cutter and terminating in said sides, an inner cutter having teeth to shearingly coat with the edges of said openings and grooves depressed in said sheet metal outer cutter plate, there being one groove for each of said openings and said grooves terminating at the ends of the openings and being of a depth substantially equal to the thickness of said outer cutter plate.

7. In a cutter head construction for dry shavers, an outer cutter plate formed of sheet metal and having a plurality of spaced openings

therein whereby the portions of the sheet metal between the openings constitute outer cutter teeth, an inner cutter having teeth to shearingly coat with said outer teeth and grooves depressed in said outer cutter plate for the openings therein, said grooves terminating at the ends of said openings and being arranged in a direction substantially parallel to the line of advance of the outer cutter plate relative to the skin of the user, said inner cutter having notched portions of its teeth adjacent said edges of said openings arranged in contact with the ends of the depressed portions of the sheet metal at the ends of said openings to shearingly coat with said ends of the depressed portions.

8. In a cutter head construction for dry shavers, an outer cutter member having a plurality of hair-reception openings therein, an inner cutter having teeth to shearingly coat with the edges of said openings and a depressed groove in said outer cutter member for each opening therein, said groove terminating at the ends of said openings, said inner cutter having portions of its teeth adjacent said ends of said openings arranged in longitudinal alignment with said groove and in contact with those portions of said outer cutter member that constitute the ends of said groove to shearingly coat therewith.

RAYMOND KNAPP.
